UNITED STATES PATENT OFFICE.

PETER K. DEDERICK, OF LOUDONVILLE, NEW YORK.

BALING-PRESS.

SPECIFICATION forming part of Letters Patent No. 654,137, dated July 24, 1900.

Application filed May 6, 1898. Serial No. 679,918. (No model.)

To all whom it may concern:

Be it known that I, PETER K. DEDERICK, a citizen of the United States, residing at Loudonville, in the county of Albany and State 5 of New York, have invented certain new and useful Improvements in Baling-Presses; and I do hereby declare the following to be a full, clear, and exact description of the same, reference being had to the accompanying drawings, forming part of this specification, and 10 to the letters of reference marked thereon.

This invention relates to improvements in presses for baling hay and other materials, and particularly to that type of such presses 15 known as "continuous" presses or in which the hay is fed into a press-chamber and ejected continuously from a bale-chamber communicating with the press-chamber, although features of the invention are applicable to other styles of presses, as will be at 20 once appreciated by those skilled in the art, and hence while I shall describe my present improvements in connection with and forming part of a continuous press I do not wish 25 to be limited specifically in this respect.

The invention has for one object to produce a simple powerful press which may be conveniently transported and operated at any convenient point without the necessity of 30 providing permanent anchors and like appliances for holding it in position while in operation.

A further object of the invention is to produce a press in which the horse sweep or power 35 may be continuously rotated and the traverser caused to reciprocate more than once for each rotation of the horse sweep or power connection and in which a sufficient pause will be provided at the extreme rearward 40 movement of the traverser to permit of the hay being fed in front of the same by hand.

A further object of the invention is to provide an improved condenser-operating mechanism which will be positively operated in 45 direct relation to the movement of the traverser to give a preliminary condensation to the charge at the moment when the traverser is at the extreme end of its rearward movement.

50 The invention consists in certain novel combinations and arrangements of parts going to form the complete press and in certain novel

details of construction, all as will be herein-after described, and pointed out particularly in the appended claims.

55

Referring to the accompanying drawings, Figure 1 is a side elevation of a baling-press with its power connection embodying my present improvements. Fig. 2 is a vertical longitudinal section through the bale-chamber and condenser. Fig. 3 is a perspective view of the forward end of the power mechanism. Fig. 4 is a detail vertical section showing the universal connection between the press-frame proper and the power end 65 and between the slide and pitman. Fig. 5 is a horizontal section on the line 5 5, Fig. 4. Fig. 6 is a detail top plan view of the ratchet-wheel and sweep or power connection. Fig. 7 is a detail perspective view of one of the 70 partitions or followers, showing the recesses for coöperation with the bell.

Like letters of reference in the several figures indicate the same parts.

Referring particularly to Figs. 1 and 2, it 75 will be seen that the bale and press chamber is of the ordinary well-known construction, formed, as usual, with angle-iron corner-pieces A, friction-clamps B at the discharge end, and inclosing sides and bottom B' in that 80 portion in which the pressing operation is done. Above the bale-chamber is a condens-ing-hopper D, also of usual construction.

Extending forward from the bale-chamber or as I shall term it "press-case" A B' and 85 preferably below the plane of the same is a pipe connection E, rigidly attached at its rear end to the press-case by clamps or cross-timbers e, and at its forward end it is provided with a casting or frame E', which is 90 adapted to be connected to the frame of the power mechanism, preferably by a universal joint to be presently described, the pipe connection itself, however, preferably lying in a plane below the joint, so as to permit a staff 95 or slide G to pass through the same from end to end, so as to facilitate the attachment of the traverser to its rear end and the attachment of the power mechanism to its forward end. The frame for the power mechanism 100 (lettered F) is provided at its forward end with a bearing f for the reception of a crank-shaft carrying at its lower end a crank G², adapted to be connected by a pitman G' with the slide

G, such connection being preferably a jointed connection, as shown at *g* in Fig. 1, to permit of a straight reciprocation of the slide and with a further object of permitting the press 5 to be transported from place to place, as will hereinafter appear.

The upper end of the crank-shaft is provided with a ratchet-wheel H, and journaled loosely upon the said shaft or upon an axis 10 coincident therewith is the power connection or horse lever or levers I, the base of the said horse-levers being preferably connected to castings or brackets I', carrying at their ends link-pawls *i*, adapted to engage with the teeth 15 on the ratchet-wheel H and be held in engagement therewith by springs *i'* or equivalent means.

Rods or braces I² may extend from the ends of each of the brackets I' to the ends of the 20 horse levers or sweeps for strengthening the same.

For the purpose of forming the universal-joint connection between the power-frame F and the pipe connection E the rear end of 25 said frame F is provided with a wrist-pin F', and the casting E' is provided with a yoke E², which passes around the same, as illustrated clearly in Figs. 4 and 5.

The connection between the rear end of the 30 slide G and the traverser K, which works in the press-case, is formed as follows: A vertical frame L is formed on the front end of the press-case, and at the top of this vertical frame a pair of sway-bars M are pivotally 35 mounted, so as to swing longitudinally of the press-case. At a point substantially in line with the horizontal center of the traverser they are pivotally connected to and support one end of said traverser, the pivotal connection 40 being formed by a pin or through-bolt *m*. At their lower ends the sway-bars are connected by links M' with the rear end of the slide G, the slide G being preferably provided with a cross-head M², to the ends of which the 45 links M' may be conveniently connected.

It is obvious now that when the slide is reciprocated by the crank and pitman the sway-bars M, together with the traverser K, will be reciprocated in unison therewith, and with a 50 view to holding the parts normally forward or with the traverser in the position illustrated in Fig. 2 the said parts are preferably provided with an automatic returning mechanism—such, for instance, as a weight—which 55 acts with a constant force, tending to move the traverser to the position mentioned and the resistance of which must be overcome in moving the traverser to compress a charge. This returning mechanism is preferably connected with the traverser itself, and for this purpose a flexible connection O, fastened at one end to the traverser, is passed around a pulley O' on the press-case, thence up over a pulley O² at the top of the frame L, and thence 60 down, and supports at its extremity a weight O³, which is sufficient for the purposes desired.

As one end of the traverser is supported by

the sway-bars M, the opposite end, resting upon the bottom of the press-case, might tend to create friction, and in order to prevent this 70 the opposite end of the traverser is preferably provided with an antifriction roller or rollers *k*, a sufficient looseness being left between the top and bottom of the traverser and the press-case to compensate for any vertical 75 movement due to the arc in which the sway-bars move. Such movement, it will be noted, however, is very slight because of the length of the sway-bars and the relatively-short movement of the traverser.

The condenser D' is reciprocated back and forth by means of the slide d, to which it is connected in the usual manner, and the said slide receives its motion from the sway-bars M, to which it is connected at *d* by a pivotal 85 connection of any usual kind.

This arrangement, it will be seen, insures a correct relative movement of the condenser and traverser, and at the moment when the traverser is at the extreme backward portion 90 of its movement the condenser will be at the extreme forward portion of its movement, thereby giving the charge a preliminary condensation, and the attendant may during the pause, while the crank is passing around its 95 dead-center, thrust the said charge down in front of the traverser and will have sufficient time to withdraw his fork or other implement without danger of the same being caught by the traverser in its forward movement.

The power-frame F, together with the press-frame, is mounted upon wheels to facilitate transportation, and the arrangement is such that the press may be readily transported and at once put into use upon its arrival at its 105 point of destination without staking or anchoring the same or removing the wheels, and with this object in view the press-frame itself is mounted upon a single pair of ground-wheels P, located somewhat centrally of the 110 press-case, although the particular location is immaterial, the axle of said wheels being preferably connected rigidly with the press-case. The rear end of the power-frame is similarly supported upon a pair of wheels P', 115 and the axle *p* of this pair of wheels is rigidly connected with the power-frame, while the front end of the power-frame is supported upon an upwardly-cranked axle *p'*, pivotally connected thereto forward of the crank-shaft, 120 and a pair of wheels P².

When it is desired to transport the press, a suitable tongue is connected to this forward axle *p'* in the same manner that a tongue is connected to a wagon, when the machine may 125 be drawn about, and by reason of the universal-joint connections between the pitman and slide and between the power-frame and pipe connection it will be found that not only may the whole press be drawn around curves and 130 turned as occasion may require, but irregularities in the surface contour of the ground traversed do not distort injuriously the various parts, for the intermediate wheels P' may

change their elevation with relation to the wheels P P^2 and still support their entire quota of weight.

It will be noted, of course, that during transportation the crank G should be turned backwardly, so as to bring the universal joint g into substantial alinement with the wrist-pin F , as illustrated clearly in Fig. 4, and, if desired, the horse levers or sweeps may either be removed entirely or turned to occupy a position longitudinally of the press.

To maintain the alinement of the power-frame F and pipe connection E when the press is in use, it is preferable to employ a single diagonal brace Q , extending from the casting E' to the axle p of the power-frame at one side, which brace Q may be readily removed or one end detached, as by a hook connection, when it is desired to move the press about.

20 In order to give the attendant notice when to place a follower in the press-case to separate the bales, I preferably provide an alarm or bell, with a means for ringing the same as each follower passes it. The bell itself is indicated by the letter R in Fig. 2, and the striker r is mounted on a spring-pressed carrier r' , which has a projection r^2 extending up through an aperture S in the bottom of the press-case and into position to engage the

30 pressed material passing through the bale-chamber, and thereby hold the striker out of engagement with the bell, but as a follower passes the projection r^2 the said projection will drop into a recess provided for this pur-

35 pose in the follower, and the striker will be brought into contact with the bell, sounding the alarm. Any desired form of recess may be provided in the follower, and in Fig. 7 I have shown a follower with two different 40 styles of recess, that at S being simply a slot cut through one edge of the follower from side to side and that at S' being a mortise in the edge of the follower, formed either by cutting the material of the follower away in the 45 form of a mortise or applying plates to the sides, as shown. The projection r^2 should be located the proper distance along the bale-chamber to allow for the formation of one bale or a multiple of bales between it and the 50 traverser when at its forward extreme of movement.

Having thus fully described my invention, what I claim as new, and desire to secure by Letters Patent of the United States of Amer-

55 ica, is—

1. In a baling-press the combination with the press-case, an upwardly-extending frame connected therewith, and a traverser working in said press-case, of sway-bars pivotally supported at their upper ends on said upwardly-extending frame and connected with the traverser for operating the same, a slide-staff mounted in fixed bearings to reciprocate longitudinally, connections between said slide- 60 staff and sway-bars below the connection between the sway-bars and traverser and a

power mechanism for reciprocating the slide-staff; substantially as described.

2. In a baling-press, the combination with the press-case, vertical frame connected therewith, sway-bars pivotally supported in said vertical frame and traverser connected with said sway-bars, of a reciprocatory slide-staff, a power mechanism for reciprocating said staff longitudinally and links connecting said 70 sway-bars and slide-staff below the connection between the sway-bars and traverser; substantially as described.

3. In a baling-press the combination with the press-case, vertical frame connected therewith, sway-bars pivotally supported in said vertical frame and traverser connected with said sway-bars, of a reciprocatory slide-staff, a power mechanism for reciprocating said 80 slide-staff longitudinally, a cross-head on said 85 slide-staff and links connecting said sway-bars and cross-head; substantially as described.

4. In a baling-press, the combination with the press-case and a pipe connection rigidly 90 connected therewith, of a power-frame jointed to the forward end of said pipe connection; substantially as described.

5. In a baling-press, the combination with the press-case and a pipe connection rigidly 95 connected therewith, of a power-frame at the forward end of said pipe connection and a universal joint connecting said power-frame and pipe connection; substantially as de- 100 scribed.

6. In a baling-press the combination with the power-frame having carrying-wheels at its front and rear ends, of a press-frame jointed to the rear end of said power-frame and also having a pair of carrying-wheels, and a power- 105 transmitting mechanism having a joint which may be brought into substantial registry with the joint between the power and press frames; substantially as described.

7. In a baling-press, the combination with 110 the press-case having a vertically-arranged frame connected therewith and the sway-bars journaled at their upper ends in said frame, of a reciprocatory traverser pivotally connected with said sway-bars, means for reciprocating the sway-bars and traverser and a vertically-movable weight connected with the traverser for returning the same to its retracted position; substantially as described. 115

8. In a baling-press, the combination with 120 the press-case, the upwardly-extending frame carried thereby, the sway-bars pivotally mounted in said frame and a power mechanism for reciprocating said sway-bars, of a traverser working in the press-case and connected with the sway-bars and a condenser located above the said press-case and also connected with said sway-bars; substantially as described.

9. In a baling-press, the combination with 125 the press-case, the condensing-hopper above the said case and the upwardly-extending

- frame carried by the case, of the sway-bars pivotally mounted at their upper ends in said frame with means for reciprocating said sway-bars and a condensing-slide and traverser 5 working in said hopper and press-case respectively, and each connected with said sway-bars and operating to compress the charges in opposite directions; substantially as described.
10. 10. In a baling-press, the combination with the press-case, traverser and means for reciprocating the traverser, of an alarm-bell

carried by the press-case, a striker adapted to contact with said bell, a resilient carrier for said striker supported by the press-case, 15 a projection on said carrier intermediate its ends projecting within the press-case and a follower having a recess into which said projection will pass to cause the striker to engage the bell; substantially as described.
